ADJUSTABLE CLOTHES HANGER

Daniel A. Eberhardt, St. Louis, Mo.

Application January 25, 1950, Serial No. 140,387

9 Claims. (Cl. 223—95)

1

This invention relates to garment hangers used for skirts and the like.

A summary statement at the outset will afford a convenient means for grasping the essence of my invention and will materially assist when reference is later had to the appended detailed description and claims.

The invention contemplates a clothes hanger which engages the inner sides of an article of wearing apparel, such as a skirt at its waistband. The article is frictionally suspended from arms which are extensible to accommodate various sizes, and self-retractable to facilitate easy removal of garments from the hanger.

The engaging arms are formed on the opposing ends of a pair of rods; such rods are maintained in longitudinal abutting parallel relationship by a pair of keepers. A keeper is associated with each of the rods and affixed thereon; the other rod being free to slide therethrough. Thus, the arms carried on the ends of the rods held by the keepers may be extended or retracted as desired.

Further, the arms are maintained in the desired position against a skirt waistband by a lock which prevents their movement away from and out of engagement with the said band.

A slidable saddle is carried on the before-mentioned rods and has a hook mounted thereon for the purpose of suspending the device from a clothes rack and the like; said saddle is kept in a central position on the rods through the action of a pair of tension springs. One such spring is mounted at each end of the slidable saddle and extended out to engage its respective arm. Another function of the said springs is to return the arms when the holding action of the lock is released.

Other advantages and objects will become apparent as the specification proceeds and a more comprehensive understanding of the invention will be afforded from the following detailed description when considered in conjunction with the accompanying drawings, in which

Fig. 1 illustrates a side elevation of the device in its retracted position;

Fig. 2 is a side elevation with sections removed showing the extended position;

Fig. 3 is a fragmentary end view showing members as they appear along line 3—3 of Fig. 1;

Fig. 4 is a section as it appears when viewed along line 4—4 of Fig. 2;

Fig. 5 illustrates in detail a locking device; and

Fig. 6 shows the locking device illustrated in Fig. 5 in its inoperative position.

For the purpose of disclosing a preferred em-

bodyment of the invention, the same has been shown and now will be described in connection with its use as a woman's skirt hanger. With reference to the drawings (Figs. 1 and 2), a pair of rods 12 and 13 lie in slidable abutting relationship and are thus held in such parallel position by a pair of keepers 14 and 15. The keeper 14 is affixed to the rod 12 and encircles, while passing, rod 13. The keeper 15 likewise is affixed to the rod 13 and passes the companion rod 12, performing a similar function as the keeper 14 associated with the rod 12. Further, the rods 12 and 13 carry, respectively, arms 16 and 17 formed at their outer ends. Arm covers 18 and 19 encase the arms 16 and 17 and are preferably made of material such as rubber or its equivalents.

Proceeding further, to maintain the arms 16 and 17 at a particularly desired extended position (see Fig. 2), a lock 21 is employed. As shown in greater detail in Fig. 5, the lock 21 includes a lever 22; said lever 22 having a bent portion 23 and is carried by means of a slot 24 on the rod 13. The slot 24, being slightly large in area, and dimensioned proportionately to the cross sectional area of the rod 13, freely passes the latter therethrough. A bowed section 25 of the rod 12 encloses the bent portion 23 of the lever 22, and prevents movement of said portion 23 to the left as viewed in the drawings. Further, a compression spring 26 encircles the rod 13 and rides thereon. The spring 26 is located between a jointure 27 of the rods 12 and 13 and the lever 22, thereby urging the bent portion 23 of the lever 22 toward the bowed section 25. This position of the lever 22 may be thought of as normal since, when the lever 22 is held thus, the edges 27 and 28 of the slot 24 form acute angles to the rod 13 gripping the same and preventing its movement toward the left as viewed in Fig. 5. As shown in Fig. 6, the lock 21 will not interfere with the extension of the arms 16 and 17 since movement of the said arms 16 and 17 outwardly causes the rod 13 to overcome the negligible resilient resistance of the lever 22.

Continuing further, a hook 29 is mounted on a saddle 30. The saddle 30, slidably mounted on the rods 12 and 13 rides between the keepers 14 and 15. A plate 31 of the saddle 30 (Fig. 3) has turned down end portions 32 and 33. End portions 32 and 33 are formed with aligned cut-out sections which permit the passage of the rods 12 and 13 thus enabling the saddle 30 to slide along the rods 12 and 13 and be retained thereon. A pair of lugs 34 and 35 on the lower ex-

tremity of turned portions 32 and 33 serve to respectively engage a pair of tension springs 36 and 37. The springs 36 and 37 are further extended to respectively bias the arms 16 and 17, being secured in notches 38 and 39 on the arms 16 and 17.

In operation the device is fitted inside of the waistband of a skirt. When located thus the arms 16 and 17 are extended against the tension of the springs 36 and 37 until the band of the skirt is firmly held by the arms 16 and 17; the arm covers 18 and 19 serving to protect the garment. The lock 21 permits the extension of the arms 16 and 17 while prohibiting any retracting when the user relinquishes hold of the device. However, to release the skirt and retrieve it from the hanger, the lever 22 is pressed towards the right as in Fig. 6, against the action of the compression spring 26. This causes the bent portion 23 to pivot against the bowed section 25 resulting in the edges 27 and 28 releasing their grasp of the rod 13. With the rods 12 and 13 thus disengaged, tension springs 36 and 37 return the arms 16 and 17 to their retracted position. Throughout, the saddle 30 is kept centrally positioned between the arms through the action of the springs 36 and 37.

Various changes, within the scope of the appended claims, may be made without departing from the spirit of the invention; parts of the invention may be used without the whole; and improvements may be added while retaining the benefits of this invention.

I claim:

1. In an adjustable clothes hanger having in combination a pair of parallel rods movable longitudinally with respect to one another, a pair of keepers holding the rods in abutting relationship, a saddle carried slidably on the said rods between the keepers, a hook secured to the saddle and operable to engage a clothes rack and the like, a pair of arms formed on the outer opposing ends of the rods to engage an inner side of a skirt waist band, a releasable lock on the rods to prevent movement of the arms toward the saddle and a pair of tension springs mounted between the saddle and the arms, respectively, to center the saddle on the rods and return the arms to a collapsed position when the lock is released.

2. In an adjustable clothes hanger having in combination a pair of parallel rods movable longitudinally with respect to one another, a pair of keepers holding the rods in abutting relationship, slidable means for suspending the rods from a clothes rack and the like, a pair of arms formed on the outer opposing ends of the rods to engage the inner side of a skirt waist band, a releasable lock on the rods operating automatically to prevent retraction of the arms but permitting extension thereof, a pair of tension springs mounted between the said suspension means and the arms respectively to center the means on the rods and return the arms to a retracted position when the lock is released.

3. In an adjustable clothes hanger having in combination a pair of parallel rods movable longitudinally with respect to one another, a pair of keepers holding the rods in abutting relationship, a saddle carried slidably on the said rods between the keepers, a hook secured to the saddle and operable to engage a clothes rack and the like, a pair of arms formed on the outer opposing ends of the rods to engage an inner side of a skirt waist band, a releasable lock on

the rods operating automatically to prevent movement of the arms toward the saddle but permitting opposite movement thereof, and resilient means mounted between the saddle and the arms to center the saddle on the rods and return the arms to a collapsed position when the lock is released.

4. In an adjustable clothes hanger having a pair of parallel rods movable longitudinally with respect to one another, a pair of keepers holding the rods in abutting relationship, a slidable saddle between the keepers comprised of an elongated plate member lying on the rods, a pair of turned down end portions each having aligned cut-out sections permitting the rods to pass therethrough formed on the plate, and a pair of lugs formed on the portions, a hook secured to the saddle to engage a clothes rack and the like, a pair of arms formed on the outer opposing ends of the rods to engage an inner side of a skirt waist band, a releasable lock on the rods to prevent movement of the arms toward the saddle and a pair of tension springs attached at the saddle by engagement with the lugs and secured to the arms operable, respectively, to center the saddle on the rods and return the arms to a retracted position when the lock is released.

5. In an adjustable clothes hanger having in combination a pair of parallel rods movable longitudinally with respect to one another, a pair of keepers holding the rods in abutting and sliding relationship, a pair of arms formed on the outer opposing ends of the rods to engage the waist band of a skirt, a releasable lock comprised of a lever positioned in part between said rod members, having a slot passing one of the rods and an end portion resiliently held against the adjacent surface of the other rod and within a bowed section thereof constructed and arranged to restrain relative movement of said rods in one direction when the lever is in a normal position and to permit relative movement in both directions when the lever is moved to an alternate position, and means for suspending the foregoing device from a clothes rack and the like.

6. In an adjustable clothes hanger having in combination a pair of parallel slidable rods, a pair of arms formed on the rods for engaging a skirt waist band, a pair of keepers for retaining the rods in abutting relationship, a locking means to secure the arms against relative inward movement but permitting outward movement thereof, a saddle mounted on the rods and movable thereon, a hook mounted on the saddle to engage a clothes rack and the like, and extensible resilient means mounted between the arms to disengage the arms from a skirt waist band and center the saddle on the rods when the action of the locking means is withdrawn.

7. In an adjustable clothes hanger having a pair of parallel rods movable longitudinally with respect to one another, a pair of keepers one affixed to a first of said rods and the other affixed to a second of the rods, each affixed keeper holding one rod in abutting relationship to the other rod, a saddle carried slidably on the said rods between the keepers, a hook secured to the saddle and operable to engage a clothes rack and the like, a pair of arms formed on the outer opposing ends of the rods to engage an inner side of a skirt waist band, a releasable lock on the rods to prevent movement of the arms toward the saddle and a pair of tension springs mounted between the saddle and the arms, respectively, to center

the saddle on the rods and return the arms to a collapsed position when the lock is released.

3. In an adjustable clothes hanger having in combination a pair of parallel rods movable longitudinally with respect to one another, a pair of keepers holding the rods in abutting relationship, 5 slideable means for suspending the rods from a clothes rack and the like, a pair of arms formed on the outer opposing ends of the rods to engage the inner side of a skirt waist band, a releasable lock on the rods operating automatically to prevent retraction of the arms but permitting extension thereof, and resilient means mounted between the slideable means and the arms to center the saddle on the rods and return the arms to a 15 collapsed position when the lock is released.

9. In an adjustable clothes hanger having in combination a pair of parallel rods movable longitudinally with respect to one another, a pair of keepers holding the rods in abutting and sliding relationship, a pair of arms formed on the outer opposing ends of the rods to engage a waist band of a skirt, a releasable lock comprised of a lever 20

positioned in part between said rod members, having a slot passing one of the rods and an end portion resiliently held against the adjacent surface of the other rod and within a bowed section thereof, constructed and arranged to restrain relative contracting movement of the rods but permitting extensive movement of the rods when the lever is in normal position, and to permit relative movement of the rods in both directions 10 when the lever is moved to an alternate position, resilient means connected to bias the rods toward a contracting position, and means for suspending the foregoing device from a clothes rack and the like.
